Augustus Anderson, INVENTOR.

BY
Geo. P. Kimmel,
ATTORNEY.

UNITED STATES PATENT OFFICE.

AUGUSTUS ANDERSON, OF TERRE HAUTE, INDIANA.

SELF-ADJUSTING DOORKNOB.

Application filed July 28, 1922. Serial No. 578,254.

To all whom it may concern:

Be it known that I, AUGUSTUS ANDERSON, a citizen of the United States, residing at Terre Haute, in the county of Vigo and 5 State of Indiana, have invented certain new and useful Improvements in Self-Adjusting Doorknobs, of which the following is a specification.

This invention relates to knob spindles 10 and has for one of its objects to provide a device of this character having means whereby the knobs are detachably and adjustably coupled to the spindle and without detaching any of the parts.

15 With these and other objects in view the invention consists in certain novel features of construction as hereinafter shown and described and then specifically pointed out in the claim, and in the drawings illustrative of the preferred embodiment of the invention:—

Figure 1 is a longitudinal sectional elevation of a pair of door knobs and their spindle, with the improvement applied,

25 Fig. 2 is a transverse section on the line 2—2 of Fig. 1.

Fig. 3 is a detail view of the plug.

The spindle is represented conventionally at 10, the knobs at 11, and the knob shanks at 12, the spindle having ratchet teeth 13 at the ends, and received by the ratchet portions in the longitudinal sockets 14 of the shanks, as shown.

35 The shanks 14 of the knobs are each likewise formed with a lateral socket 15 communicating with the longitudinal socket and with an obliquely directed guideway 16 communicating with the lateral socket.

Movably disposed within each lateral 40 socket is a plug 17 having a "toe" 18 at the inner end to engage one of the ratchet teeth 13 and with a laterally enlarged head 19 extending over the adjacent portion of the shank.

45 Formed in one side of each of the plugs 17 is a seat 20 to receive the inner end of a spring 21 within the guideway 16, and held in place by a threaded holding pin 22. By this means the plug 17 is yieldably supported in engagement with the spindle, and by employing a plurality of the ratchet teeth, it is obvious that the knobs may be adjusted upon the spindle to correspond to the thickness of the door to which the device is applied.

Each of the head portions 19 is formed with a small cut away portion indicated at 23, to receive a point of a small screw driver, or the like to permit the plug 17 to be forced outwardly a sufficient distance against 60 the resistance of the spring 21, to release the "toe" portion 18 of the plug from engagement with the ratchet teeth and thus release the knob.

In applying the knobs, the inclined faces 65 of the ratchet teeth permit the knobs to be forced to any required distance upon the spindle.

The improved device is simple in construction, can be simply constructed and at 70 a trifling additional expense. By forming the ratchet relatively small, the adjustments can be correspondingly slight to adapt the device to small differences in the thicknesses 75 of doors.

The preferred embodiment of the invention is disclosed in the drawings and set forth in the specification, but it will be understood that modifications within the scope of the claimed invention may be made in the 80 construction without departing from the principle of the invention or sacrificing any of its advantages.

Having thus fully described the invention, what is claimed is:—

A device of the class described comprising a knob and its shank with a longitudinally directed socket and a laterally directed guideway in the shank communicating with the socket and an obliquely directed guideway communicating with the laterally directed guideway, a spindle movable in the socket and having a plurality of ratchet teeth, a plug movably engaging in said laterally directed guideway and with a tooth 95 at the inner end to engage the teeth of the spindle one at a time and laterally enlarged at the outer end to bear upon the shank when in operative position to hold the plug from abnormal inward movement, said plug 100 having a V shaped recess registering when in one position with the obliquely directed guideway, a spring within the guideway and engageable at one end in the recess of the plug, and means for holding said spring 105 within the guideway.

In testimony whereof, I affix my signature hereto.

AUGUSTUS ANDERSON.
